US0D1112038S

(12) **United States Design Patent** (10) Patent No.: **US D1,112,038 S**
Chen et al. (45) Date of Patent: ** Feb. 10, 2026

(54) **BATTERY**(71) Applicant: **XIAMEN HITHIUM ENERGY
STORAGE TECHNOLOGY CO.,
LTD.**, Fujian (CN)(72) Inventors: **Linqing Chen**, Fujian (CN); **Li Zhang**, Fujian (CN)(73) Assignee: **XIAMEN HITHIUM ENERGY
STORAGE TECHNOLOGY CO.,
LTD.**, Fujian (CN)(***) Term: **15 Years**(21) Appl. No.: **29/931,656**(22) Filed: **Mar. 7, 2024**(30) **Foreign Application Priority Data**

Sep. 8, 2023 (CN) 202330585800.4

(57) **CLAIM**

The ornamental design for a battery, as shown and described.

DESCRIPTION

FIG. 1 is a first perspective view of a battery according to the present design;

FIG. 2 is a second perspective view of the battery according to the present design;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
